UNITED STATES PATENT OFFICE.

ALEXR. H. HART, OF CHAGRIN FALLS, OHIO.

TWYER.

Specification of Letters Patent No. 5,479, dated March 21, 1848.

To all whom it may concern:

Be it known that I, ALEXANDER H. HART, of Chagrin Falls, in the county of Cuyahoga and State of Ohio, have invented a new 5 and Improved Mode of Constructing Twyer-Irons for Blacksmiths' Forges; and I do hereby declare the following is a full and exact description.

The nature of my invention consists in 10 constructing a twyer which forms a bed or lap for the burning coals, furnished with two orifices for the escape of the wind opposite to each other, which orifices are so connected with a revolving valve by which 15 the blast can be directed in whole or in part through one or both of the orifices at the same time, or otherwise regulated to suit the convenience of the artisan.

To enable others skilled in the art to make 20 and use my invention I will proceed to describe its construction and operation reference being had to the annexed drawings making a part of his specification.

Figure 1 represents the twyers with all 25 the parts in their proper places and ready for use. Fig. 2 represents the lower section of the twyer. Fig. 3 represents the dividing plate or diaphragm. Fig. 4 represents the upper half of the tube or nozzle of the 30 twyer. Fig. 5 is a ring for binding the two halves of the tube. Fig. 6 represents the under surface of the upper section of the twyer. Fig. 7 represents the circular valve. Fig. 8 is a section of the twyer in a vertical 35 direction.

Letter A Figs. 1 and 8 represents the opening into which is to be inserted the nose of the bellows pipe; letter B is the chamber containing the revolving circular valve, letter 40 D Figs. 1 and 8 and letter E Figs. 1 and 8 are the orifices for the blast.

Letter F Fig. 1 is the bed or lap for containing the coals and letter C Fig. 1 is the stem of the valve.

45 The twyer is made of metal, cast-iron is preferred and is composed of three principal sections Figs. 2, 4 and 6. Fig. 2 represents the main or bottom section, letter B the lower half of the valve chamber, letter G the channel through which the blast is conveyed to the orifice D Figs. 1 and 8. This channel is separated from the one which conveys the blast to the orifice E Figs. 1 and 8 by a diaphragm C Figs. 3 and 8 made of a thin plate 50 of metal the end marked a Fig. 3 coming in

contact with the surface of the cooling valve Fig. 7. The operation of these two parts will be further explained hereafter. Fig. 4 represents the upper portion of the pipe and valve chamber A B Figs. 1 and 8. 60 This part Fig. 4, is fitted to the lower half air-tight and secured by a band Fig. 5 which embraces the ends of both parts shown at A Fig. 1, the other end being secured to the under section by a clasp which embraces 65 both parts immediately forward of the valve chamber, the cap of this clasp is secured by nuts shown at a a Fig. 1 and at a Fig. 8. Fig. 6 represents the under side of the upper section of the bed or lap. This section is 70 represented in its proper place in Fig. 1 letters b b; the under side is grooved out thus forming a channel for the passage of the air to the orifice E Figs. 1 and 8, the groove is shown in section at G Fig. 8. This section 75 is secured to the bottom piece by the end or point a Fig. 6 passing under a portion of the cap and secured by a key as shown at c Figs. 1 and 8. The outer ends are clasped together by a band passing around a projection on both sections as shown at H Fig. 1 and at I Fig. 8. The valve, Fig. 7 is a solid cylinder with the exception of a mortise through the center which mortise is wedge shaped as represented at a b c Fig. 7 and 85 in section at F Fig. 8. The stem of this cylinder valve passes through the front side of the valve chamber as shown at C Fig. 1 for the purpose of revolving the valve.

The operation of this twyer is as follows: 90 If the blast is desired at the orifice D Figs. 1 and 8 the cylinder is turned so that the upper edge of the small end of the mortise is below the diaphragm C Figs. 3 and 8 the air is thus conveyed along the channel G 95 Fig. 2 and H Fig. 8 to the aperture D Figs. 1 and 8. If the blast is required at the orifice E, the cylinder valve is turned upward so that the lower edge of the small end of the mortise is even with the upper side of the diaphragm. The air is thus conveyed along the groove or channel cut or cast in the under side of the section Fig. 6 in the direction of the arrows, this groove is shown in section by the dotted lines G Fig. 8 and opening in the orifice E Figs. 1 and 8. If it is desired to divide the blast into two equal parts issuing at the same time from both orifices D and E Figs. 1 and 8 the cylinder or revolving valve is turned so that the small 110

end of the mortise is divided by the dia-
phragm. The blast is directed into each of
the channels and escapes into the fire at
both orifices. The blast can also be varied in
5 regard to quantity or strength by partially
closing the channels or turning the valve, or
the blast may be entirely cut off by turning
the cylinder so as to bring the mortise per-
pendicular should the section Fig. 6 become
10 injured by heat it can at a trifling expense
be replaced. By loosening the key at *c* Figs.
1 and 8 and the band at *H* Fig. 1 and *I* Fig.
8 the injured part can be removed and a new
one returned.

What I claim as my invention and desire 15
to secure by Letters Patent is—

The construction of a twyer having two
orifices for the escape of the blast, in com-
bination with a revolving valve and dia-
phragm, so that the blast may be light or 20
heavy through one or both of the orifices, the
whole forming a bed or lap for the burning
coals, substantially as herein described.

A. H. HART.
